UNITED STATES PATENT OFFICE.

CHARLES R. ELY, OF CHAMPLAIN, NEW YORK, ASSIGNOR TO THEODORE W. SHERIDAN, OF BROOKLYN, NEW YORK, AND CHARLES B. SHERIDAN, OF ORANGE, NEW JERSEY.

PAPER-CUTTING MACHINE.

SPECIFICATION forming part of Letters Patent No. 449,525, dated March 31, 1891.

Application filed October 23, 1890. Serial No. 369,113. (No model.)

To all whom it may concern:

Be it known that I, CHARLES R. ELY, a citizen of the United States, residing at Champlain, in the county of Clinton and State of New York, have invented new and useful Improvements in Paper-Cutting Machines, of which the following is a specification.

This invention relates to improvements in paper-cutting machines; and it consists in certain devices and combinations set forth in the following specification and claims, reference being had to the accompanying drawings, in which—

Figure 1 is a front elevation of a machine containing my invention, the knife being shown in its raised position. Fig. 2 is a side elevation of a section taken on the line xx of Fig. 1, looking in the direction of the arrow 1. Fig. 3 is a section taken on the line yy of Fig. 5, looking in the direction of arrow 2. Fig. 4 is a rear elevation of the machine. Fig. 5 is a section taken on the line zz of Figs. 3 and 4, looking downward. Fig. 6 is a horizontal section in the plane $x'x'$.

The machine represented is of the class in which the resistance offered to the knife by the paper reacts upon the clamp which holds the paper on the table.

The letter A designates the frame of the machine, which supports a table B, upon which the paper to be cut is placed.

C is the clamp, and D the knife, both arranged above the table B. The clamp is connected to a clamp-slide C', which is arranged under the table, the rods $b b$, which connect the clamp to the clamp-slide, passing through the table. The knife projects downward from the knife-stock D', which is provided with lugs $d d$, that extend into oblique slots $a a$, formed on the upper part of the frame, the arrangement being such that the knife-stock and knife when the machine is operated are moved up and down obliquely toward and away from the table. The knife-stock D' is connected to a slide E by means of the lever H, which is pivoted to the frame at e , the upper end of said lever H being connected to the knife-stock by a link f , while its lower end is connected by a link h to slide E. The

slides C' and E are guided in their motions in vertical ways formed on the lower part of the frame. The clamp and the knife are both operated by means of a shaft F, which is situated between the slides and which carries pinions K L, that mesh with racks I J, placed on the slides C' and E, respectively. The shaft F is fitted in vertical slots g , formed in the frame of the machine, and is capable of a compound revolving up-and-down motion. When the clamp C and knife D are in an upper position, the shaft F rests in the lower ends of the slots g , as shown in Figs. 2 and 3. When a revolving motion is imparted to the shaft F in the direction of the arrow marked near it in Fig. 3, the pinions K L act upon the racks I J and the clamp-slide C' receives a downward motion, while the knife-slide E is moved upward, causing the descent of the knife. The shaft F remains at the lower ends of the slots g until the clamp C is brought to bear on the paper to be cut and the clamp-slide C' ceases its motion, when the pinions L, meshing with the racks J of the clamp-slide, climb upon the said racks J and cause the shaft F to travel upward in the slots g with a revolving motion, the knife-slide E meanwhile being forced farther upward by the action of the pinions K on its racks I, so as to cause the knife to descend still farther and complete its cut through the paper. As the pinions L climb the racks J of the clamp-slide, they act upon the clamp-slide with a tendency to draw the same with the clamp downward, and since the resistance of the knife-slide E to the action of the shaft F or its pinions K increases as the knife meets with the resistance of the paper this increasing resistance is added to the tractive action of the shaft on the clamp-slide, so that the resistance offered to the knife reacts upon the clamp, and the pressure of the clamp is proportionate to such resistance. The lever H by which the knife is connected to its slide E has its fulcrum on a pivot e , which is so arranged that it allows the clamp to descend with greater speed than the knife, so that the clamp is brought to bear upon the paper before the knife begins to cut and the correct

operation of the machine is insured. The accelerated movement of the clamp is increased by arranging the clamp in advance of the knife. When the clamp ceases to move downward and the pinions L climb the racks J of the clamp-slide and cause the shaft F to rise, as before stated, the upward motion of the shaft is added to the revolving motion thereof in its action on the knife-slide with the result to increase the speed of the descent of the knife, and since this occurs just before the knife begins to cut the knife forces its way through the paper with an accelerated movement. The advantage thus gained is a saving of time.

A revolving motion is imparted to the traveling shaft F from a driving-shaft G, which has its bearings in journal-boxes secured to the frame A. On this shaft are loosely mounted two pinions m m' , which can be thrown in gear with said shaft by a clutch mechanism M, one end of which is provided with a friction-cap m^2 to engage the conical hub of the pinion m , while its opposite end is provided with a spur-disk m^3 to engage a corresponding disk formed on the hub of the pinion m' , Figs. 4 and 5.

N is an intermediate shaft, which is mounted in brackets n n' , Figs. 4 and 6. These brackets swing loosely upon the driving-shaft G, and in the bracket n is secured a stud n^2 , on which is mounted a pinion n^3 , Figs. 2 and 4, which gears into a pinion n^4 , firmly mounted on the intermediate shaft N. This pinion engages a cog-wheel f' , firmly mounted upon the traveling shaft F, and on this shaft are loosely mounted two straps f^2 f^3 , which embrace the intermediate shaft N and serve to keep these two shafts at a uniform distance apart. On the intermediate shaft N is also mounted a cog-wheel n^5 , which engages the pinion m' on the driving-shaft G, and if this pinion m' is thrown in gear with the driving-shaft G and this shaft is turned in the direction of arrow 1, Fig. 2, the intermediate shaft N receives motion by the action of the pinion m' upon the cog-wheel n^5 , and this motion is transmitted through the pinion n^4 and cog-wheel f' to the traveling shaft F, causing the same to revolve in the direction of arrow 1, (marked near the cog-wheel f' in Fig. 2,) so that the clamp C and the knife D are caused to descend, as already explained. After the knife has completed its downward stroke the clutch mechanism is reversed, so as to throw the pinion m in gear with the driving-shaft and to transmit motion to the traveling shaft F by means of the pinions n^3 n^4 and cog-wheel f' , Fig. 2, causing this cog-wheel, and consequently the shaft F, to revolve in the direction of arrow 2, Fig. 2, whereby the clamp and the knife are both moved up and returned to the position shown in the drawings. During the up-and-down movements of the traveling shaft F the brackets n n' swing upon the driving-shaft G, but the pinions m n^3 n^4 and cog-wheel f' remain in gear with each other, while

pinion m' remains in gear with cog-wheel n^5 , so that whether the pinion m or m' be clutched to the driving-shaft G, the rotary motion of the latter is positively transmitted by gearing to the traveling shaft F.

I am aware of the machine described in Patent No. 223,744, granted to Edwin R. and Theodore W. Sheridan, assignees of A. Malm, January 20, 1880, in which latter machine the revolving motion is transmitted from the driving-shaft to the traveling shaft through a universal joint, and the intermediate shaft simply serves to reverse the motion of the traveling shaft. In my machine the universal-joint connection is dispensed with and the intermediate shaft N serves the double purpose of transmitting a rotary motion from the driving-shaft to the traveling shaft and also of reversing this rotary motion.

On the hub of the pinion m' is placed a strap O, which acts as a brake, whereby this pinion is prevented from turning by frictional contact, while the driving-shaft continues to rotate and the operating parts of the cutting-machine are stationary. This strap is elastic and is compressed upon the hub of the pinion m' by a dog o, which swings on a stud o', Figs. 3 and 5; and the tail end of which carries a set-screw o², which bears upon a wedge o³, attached to the lever P, which serves to shift the clutch mechanism. When this lever is moved so as to throw the clutch-sleeve out of gear with both the pinions m and m' , the dog o is moved so as to compress the strap O on the hub of the pinion m' , and the action of said strap upon the hub can be regulated by the set-screw o².

What I claim as new, and desire to secure by Letters Patent, is—

1. In a paper-cutter, the combination, with a knife-stock D', a clamp C, a driving-shaft G, a traveling shaft F, and devices actuated by the driving-shaft to operate the knife-stock and clamp, of an intermediate shaft N, swinging brackets n n' , hung on the driving-shaft and supporting the intermediate shaft, swinging straps f^2 f^3 , hung on the traveling shaft and connected with the intermediate shaft, and gearing between the traveling, intermediate, and driving shafts, substantially as and for the purpose described.

2. In a paper-cutter, the combination, with the knife-stock D', the clamp C, the driving-shaft G, and the traveling shaft F, of the intermediate shaft N, having its bearings in brackets n n' , which swing upon the driving-shaft, the straps f^2 f^3 , which connect the traveling shaft and the intermediate shaft, the cog-wheel f' , mounted on the traveling shaft, the pinion n^4 , mounted upon the intermediate shaft and meshing into the cog-wheel f' , the pinion n^2 , mounted on a stud in the bracket n and meshing into pinion n^4 and also into the pinion m , mounted loosely on the driving-shaft G, the cog-wheel n^5 , mounted on the intermediate shaft and gearing into the pinion m' , mounted loosely on the driving-shaft, and

the clutch mechanism between the pinions m and m' , substantially as described.

3. In a paper-cutter, the combination, with the knife-stock, the clamp, the driving-shaft, and mechanism for imparting to the knife-stock and to the clamp a reciprocating motion, of two pinions m m' , mounted loosely upon the driving-shaft, a clutch mechanism between the two pinions, a strap O , extending round the hub of the pinion m' , a dog o for compressing the strap around the hub, and

a wedge o^3 , which acts upon the dog and is actuated by the clutch-lever P , substantially as described.

In testimony whereof I have hereunto set my hand in the presence of two subscribing witnesses.
